UNITED STATES PATENT OFFICE.

JAMES SWAN, OF SEYMOUR, CONNECTICUT.

BIT-HOLDER.

SPECIFICATION forming part of Letters Patent No. 337,858, dated March 16, 1886.

Application filed January 2, 1886. Serial No. 187,363. (No model.)

To all whom it may concern:

Be it known that I, JAMES SWAN, a citizen of the United States, residing at Seymour, in the county of New Haven and State of Connecticut, have invented certain new and useful Improvements in Bit-Holders; and I do hereby declare the following to be a full, clear, and exact description of the invention, such as will enable others skilled in the art to which it appertains to make and use the same.

My invention has for its object to produce a device of this class which shall be adapted for holding bits in place in boxes for transportation, and shall also be adapted for holding them in place in workshops, or wherever they may be when not in use. It is of course essential in devices of this class that they shall be simple and economical in construction, always ready for use, and practically impossible to get out of order. In order to accomplish these results, I have devised the novel bit-holder, of which the following description, in connection with the accompanying drawings, is a specification, numbers being used to indicate the several parts.

Figure 1 is a plan view of a bit-box opened, showing my invention as applied in the packing of bits for transportation. Fig. 2 is a cross-section of the box and bit-shanks on the line *x x* in Fig. 1.

1 indicates the box, and 2 bits. 3 is the bit-holder, which is made of a piece of spring metal bent in the form shown—that is, provided with circular loops or sockets 4, which receive and closely embrace the shanks of the bits.

An important peculiarity of my construction is that the loops or sockets are so formed as to press upon considerably more than half the surface of the shanks—that is to say, the holder is so formed that spring projections 5 partially close the openings 6 into the sockets. These projections of course yield as the bits are forced in, then spring back into place, thus holding the shanks firmly within the loops or sockets. At the bottom of each loop or socket a hole is provided to receive a nail or screw, 7, by which the holder is secured in position. It will thus be seen that each socket is independent of the others, so that one, two, or any number of them may be used without affecting the others.

8 is a strip, to which the holder is secured in any suitable manner. This strip I preferably make of wood, as indicated in Fig. 2, and provide 55 curved recesses or depressions to receive the loops or sockets, but made slightly larger than said loops or sockets. The curved sides of these depressions act to support the loops or sockets. They are made sufficiently wide to 6: allow the projections to open to receive the bit-shanks, but at the same time support the holder just at the point where support is most needed.

By using strips with the curved depressions 65 I am enabled to make the spring-holders of much lighter metal than would otherwise be necessary, and at the same time to secure equally satisfactory results.

When used in packing bits for transportation, the shank of each bit is pressed into a socket, and the bit is given two or three turns to engage the point thereof, or gimlet, with the wood of the box, as is clearly indicated in Fig. 1.

I have found in practice that no matter how much the boxes are tumbled about in transportation the bits never become loose.

When placed against a wall as a holder for bits in a workshop, or in any similar use, the 80 holder may be used without any backing, as in Fig. 4, with the metallic backing, as in Fig. 3, or with the backing having the curved depressions, as in Fig. 2.

When used for holding augers or large-sized 85 bits, the latter form will be found preferable.

Variations in the details of construction may of course be made, within reasonable limits, without departing from the spirit of my invention.

I claim—

1. A bit-holder consisting of a strip of metal bent to form loops or sockets to receive the shanks, and having the openings to said loops or sockets partially closed by spring projections 95 5, and a backing provided with curved depressions, in which the loops or sockets are secured, and which form a support therefor.

2. The combination, with a metallic strip bent to form projections 5, and loops or sockets 4, which are provided with holes at their bottoms, of a backing having depressions, in which the loops or sockets are secured by screws 7, and whose curved sides serve as a

support for said loops or sockets, as and for the purpose set forth.

3. The combination, with box 1 and backing 8, having depressions 9, of a strip of spring metal bent to form sockets 4, and projections 5, and secured to said backing by screws or nails 7 at the bottoms of said sockets.

In testimony whereof I affix my signature in presence of two witnesses.

JAMES SWAN.
